UNITED STATES PATENT OFFICE.

MAX KELTING, OF BOCHUM, GERMANY.

BOILER PLANT.

Application filed August 7, 1924, Serial No. 730,653, and in Germany March 5, 1924.

My invention refers to boiler plants and its object is to provide means whereby the utilization of heat in boiler plants is increased and rendered more efficient than has 5 hitherto been possible.

In boiler plants comprising means for heating the boiler with gaseous, liquid or solid finely subdivided fuel, such as pulverized coal, the heat energy of the fuel has 10 been stored in periods of lower steam consumption by heating a heat storage such as Cowper's stove in order to be able during periods of higher steam consumption to preheat the air of combustion by causing it to 15 pass through the heat storage. In boiler plants heated with coke oven gas or blast furnace gas the continually flowing current of gas can be consumed in spite of the non-uniform steam consumption, the provision 20 of gas tanks being thereby avoided. But also in boiler plants heated with other kinds of fuel the storing of the heat has proved useful inasmuch as by preheating the air of combustion the steam production can be increased 25 50% or more without the volume of flue gas becoming larger and without the temperature of the waste gases being raised, the heated air of combustion not only increasing the heat supply, but also the useful 30 drop in temperature and in consequence thereof also the steam production. In the boiler plant according to the present invention the boiler is combined with the heat storage in such manner that the gases of 35 combustion issuing from the burner, which is common to both parts of the combination, can be distributed according to requirements. It is thus possible to supply only so much heat to the boiler as corresponds to 40 the heat consumption for the time being, the steam in excess being led into the heat storage. If the steam consumption rises, a simple reversal will cause the air of combustion to pass through the heat storage, 45 taking up the heat stored therein so that in this manner the excess heat resulting from a former operation is led back below the boiler. In consequence thereof the supply 50 of fuel and air need be regulated only at larger intervals, if it is found that the heat storage receives too much or too little heat. In gas heated furnaces or in furnaces provided with a burner fed with oil or pulverized coal by means of an air or steam jet 55 the energy of flow of the jet can be utilized for simplifying the reversal or regulation.

Referring to the drawings, *a* is the upper drum and *b* are the tubes of a water tube boiler, which are heated by the fire gases in the usual manner, the gases of combustion escaping through the main flue *c*. *e* is a burner supplied with gas, oil or pulverized fuel from a main *d*. In periods of low steam consumption, for instance in the intervals between two hoisting operations in a mine, 60 the burner aspirates cold air from without through the fresh air conduit *f* and carries it along through the mixing nozzle *g* into the combustion chamber *h*. Underneath this chamber the heat storage *i* is mounted comprising a refractory checker work of some well known kind. *k* is an opening in the bottom of the combustion chamber forming a connection between this chamber and the heat storage, whereby part of the fire gases 65 is drawn through the heat storage *i*, giving off its heat energy and escaping through the conduit *l* into the main flue *c* provided that the reversible flap *m* assumes the position shown in Fig. 1.

If the heat storage *i* is heated up in this manner and if the steam consumption increases, the reversible flap *m* is shifted into the position shown in Fig. 2. Inasmuch as this operation takes place at the cooler end of the heat storage, no difficulties are encountered, inasmuch as no parts need be operated which are exposed to greater heat. With the reversible flap *m* in the position shown in Fig. 2, the sucking action of 70 burner *e* will now cause fresh air from without to be drawn in through the conduits *n* and *l*, this air being compelled to travel across the heat storage *i* before entering the conduit *o* and mixing with the fuel escaping from the burner *e*. The opening *k* need not be closed, inasmuch as the greatest part of the hot air will pass through the conduit *o*, inasmuch as the air traveling across the heat storage and being heated therein has a greater buoyancy, being aspirated more vigorously by the burner and the main flue than cold air.

If the reversible flap *m* is adjusted for throttling the supply of air to the heat storage, the balance of cold air is introduced by way of the conduit *f*. In consequence thereof the reversible flap *m* also provides for a suitable mixing of cold and hot air. If the reversible flap *m* is placed in an intermediate position, the heat storage or generator *i* is thrown out of action not only as a heat stor- 100 105 110

age, but also as air heater. This position is imparted to the reversible flap during periods of average steam consumption where the consumption of steam corresponds to 5 the normal quantity of fuel consumed in the furnace, if this latter is supplied with cold air from without.

A boiler plant combined with a heat storage as shown and described can be operated 10 in the simplest manner and even more easily than an ordinary boiler. With a uniform supply of fuel the attendant need merely adjust the reversible flap in correspondence to the variations of steam pressure, a fresh 15 regulation of the burner becoming necessary only when greater differences arise between the heat energy to be distributed on the boiler and the heat storage on the one hand, and steam consumption on the other hand. 20 Obviously the operation of the reversible flap can also be effected by any of the well known automatic devices, for instance from a piston acted upon by the steam pressure in the boiler.

25 I wish it to be understood that I do not desire to be limited to the exact details of construction shown and described, for obvious modifications will occur to a person skilled in the art.

30 I claim:—

1. Boiler plant comprising a boiler, a source of hot gases, a heat storage and means whereby either said hot gases are made to flow partly in contact with said boiler and 35 partly through said heat storage or fresh

air is drawn through said heat storage and caused to mix with said hot gases.

2. Boiler plant comprising a boiler, a burner, a heat storage and means whereby the hot gases emanating from said burner 40 are made to flow partly in contact with said boiler and partly through said heat storage or fresh air is drawn through said heat storage and caused to mix with said hot gases.

3. Boiler plant comprising a boiler, a 45 heat storage, a fresh air conduit leading below said boiler and to said heat storage, a burner projecting into said conduit, a main flue and reversing means whereby either the hot gases emanating from said burner are 50 made to flow partly in contact with said boiler and partly through said heat storage or fresh air is drawn through said heat storage in opposite direction and caused to mix with said hot gases. 55

4. Boiler plant comprising a boiler, a heat storage, and a direct connection between said heat storage and the lower side of said burner, a fresh air conduit leading below said boiler and to said heat storage, a burner projecting into said conduit, a main flue and reversing means whereby either the hot gases emanating from said burner are made to flow partly in contact with said boiler and partly through said heat storage or fresh air is 60 drawn through said heat storage in opposite direction and caused to mix with said hot gases. 65

In testimony whereof I affix my signature.
MAX KELTING.
